DENTAL ARTICULATOR

Ralph A. Pittman, Eldorado, Ark., and Joseph A. Gardner, Memphis, Tenn.

Application January 28, 1937, Serial No. 122,698

5 Claims.

(Cl. 32—32)

This invention relates to improvements in devices for holding models of portions of the human jaws and teeth in articulated relation.

It relates to an articulator from which the models may be removed, in order that they may be worked on or reproduced, and in which the models themselves or reproductions thereof may be again secured, and removed as often as it may thereafter be found necessary.

10 It particularly relates to a device of this kind in which upper and lower holder portions of the device or holders, and the models carried thereby, have relative lateral motion about a central pin and forward and/or rearward motion relative to each other along the median line of the holder.

15 It further relates to a device having such relative motions in which lateral motion also causes a rearward motion, and to a device in which rearward motion of the upper holder accomplishes a separation of the two holders and the models carried thereby, and a longitudinal forward motion of such holder permits approach of the holders and models carried thereby.

20 25 It further relates to such a device in which the upper and lower holders normally remain in a fixed relation, both longitudinally and laterally.

Articulators have previously been known in which some of the results above enumerated have 30 been accomplished by much more elaborate but less satisfactory means.

The objects of the present invention are:

To provide an articulator having centering means positioned on the median line of the holders and carried by one thereof, and in which the other said holder is oscillatable about said means and longitudinally movable with regard thereto, both of said movements being resiliently opposed.

40 To provide an articulator having a pair of relatively movable model holders, in which movement, longitudinally and laterally, is centered by a pin carried by one of said holders and in which lateral movement also causes a longitudinal movement, all of said movements being resiliently opposed.

45 The means by which the foregoing and other objects are accomplished and the manner of their accomplishment will be readily understood from 50 the following specification on reference to the accompanying drawing, in which,—

Fig. 1 is a side elevation of the articulator;

Fig. 2 is a plan view;

Fig. 3 is a corresponding fragmentary section 55 taken on the broken line III—III of Fig. 1;

Fig. 4 is a fragmentary section taken on the line IV—IV of Fig. 2;

Fig. 5 is a side elevation showing a modified form of the device;

Fig. 6 is a fragmentary section taken on the line VI—VI of Fig. 5; and

Fig. 7 is a fragmentary section taken on the line VII—VII of Fig. 5.

Referring now to the drawing, in which the various parts are indicated by numerals, 10 and 11 are respectively upper and lower holders adapted to releasably hold models 12 and 13, as of the upper and lower teeth and related jaw structures. 14 is a post integral with and extending upward from the lower holder 11. 15 is a substantially horizontal extension, disposed rearwardly, of the upper end of the post and connected thereto by a short, upwardly inclined portion 16, the extreme rear end of the extension being faced at right angles to the longitudinal center line of the holder 11. 17 is a pin rigidly secured in the extension 15 and extending upward therefrom. Resting on the upper surface of the extension 15, is a block 20, in which is formed a slot 21, adapted to slidably receive the pin 17. At its outer end this block has a downwardly extending flange 22, adapted to seat against the end of the extension 15. 23 is a spring, secured as by screws 24 to the holder 11, the upper end of this spring contacting the rear end of the block 20 and resiliently holding the flange 22 against the end of the extension 15. It will be noted that the width of the rear end of the extension and of the flange are such that any lateral relative movement of the holders will shift the upper holder relatively rearward with respect to the lower holder, the slot 21 permitting such movement relative to the pin, and that such movement is resisted by the spring 23. This spring, acting against the flange 22 to hold the flange against the extension 15, accomplishes the longitudinal centering of the block relatively to the lower holder.

24 is a nut ordinarily loosely contacting the upper surface of the block 20 to hold the same in place, but permitting turning and sliding; and 45 25 is a lock nut. It will be noted, however, that if it be so desired these nuts may be used to tightly clamp the block against the upper surface of the extension 15.

50 The rear end of the upper holder 10 is forked to provide arms 26, which are disposed to the opposite sides of the block 20 and are pivotally connected thereto, as by screws 27. 28 is a thumb screw and 29 a lock nut therefor, the 55

screw 28 being threadedly screwed through a portion of the holder 10, with its end seated on the inclined portion 16 of the extension 15, and being adjustable to vary the distance between the holders 10 and 11. 30 are lugs, extending downward from the block 20 on opposite sides of the extension 15, which lugs serve to limit the lateral swing of the block and the upper holder secured thereto, relative to the extension 15 and the lower holder 11.

In Figs. 5, 6 and 7, 10A and 11A are respectively the upper and lower holders, 14A the upwardly extending post, 16A the inclined portion of the extension 15A, and 23A the spring. In this modification the underside of the block 20A is chambered out to receive the extension 15A, thus providing oppositely disposed sides 40 and a rear end 41, the latter corresponding to the flange 22. The sides 40 are inwardly thickened at their forward edges 40A, so that they confine the extension 15A as closely as is possible and yet allow the lateral movement of the holder 10A. The rear end of the extension 15A is peaked, having a centrally disposed apex 42, and the inner surface 25 of end wall 41 has a complementary shape. The spring 23A normally holds the end wall 41 against the end of the extension 15A, and by coaction between their complementary surfaces and the engagement of the thickened side portions 40A 30 of the block with the extension, act to normally hold the block and the holder 10A carried thereby, longitudinally centered. It will be noted from Fig. 6, which is a section through the upper portion of the block 20A, that the hole 21A, through 35 which the pin 17A passes, is enlarged to permit lateral movement of the block relative to the pin.

From the foregoing description it will be seen that direct longitudinal and lateral movement of the one holder with respect to the other is 40 accomplished about the pin 17, which is located on the longitudinal center or median line of the two holders, that separation of the holders during longitudinal movement is accomplished by co-acting parts adjacent this pin, and that longitudinal movement due to lateral movement, is 45 accomplished through the end of the extension 15, or 15A, and the complementary end flange or portion of the block 20, or 20A, all of which lie adjacent to this pin, thus freeing the articulator 50 of widely separated parts for accomplishing such movements and making the articulator compact and easy to manipulate, particularly in observing and relatively shifting models to determine their fit under conditions analogous to those of 55 the finished teeth in the mouth, as when biting with the front teeth or grinding with the rear teeth or molars.

In using the device, models are formed substantially as set out in our prior Patent No. 60 2,094,903, during this forming operation the nuts 24 and 25 preferably being clamped to rigidly hold the upper and lower holders in their normal relation. The first models are made of plaster of Paris, or other comparatively soft 65 dental investment material. After completion of these models the nuts 24 and 25 are released and the two models may be moved relatively to each other for examination and other purposes. In doing this, the concentration of central parts adjacent the pin 17 permit the thumb to be placed 70 against the post 14, and the forefinger around the model 12. By contraction of thumb and finger the lower holder may be moved forward relative to the upper holder to bring the front teeth into 75 occlusion and enable the bite of the teeth to be

examined and, if necessary, correction be made to correct the bite. In this movement it will be noted that the screw 28 slides upward along the inclined portion 16 of the extension, separating the back teeth, as is done by the equivalent 5 movement of the jaws and permitting the front teeth to be properly brought together, with the back teeth separated. With the front teeth in biting contact the front ends of the holders may be laterally shifted and necessary correction in 10 bite observed and made.

With the upper holder held in normally retracted position by the spring 23 and properly centered by the spring and abutting parts, the rear teeth should be in perfect contact and, if 15 the faults may be observed and corrected. In such position one holder may be shifted laterally with respect to the other by suitable movement of the thumb and finger. In such lateral shifting the flange 22, being in contact with the 20 rear end of the extension 15, advances the lower jaw relatively to the upper jaw for any movement away from a central position, the resulting movements conforming to those of the teeth in the mouth. In this action the lugs 30 limit the 25 amount of lateral shifting. Whenever the models are released from manual pressure the spring 23 restores the two holders to their initial alignment. It will be understood also that after examination is made from one side by grasping post 30 and model with thumb and finger respectively, that the articulator is usually reversed and post and model are grasped from the opposite side by finger and thumb respectively.

When completed both models, or either model 35 is turned over to the laboratory to make bridges, plates, or the like, as may be desired. When the laboratory has completed its work the dentist may assemble the completed work in his articulator and examine the normal setting of the rear 40 teeth and their action, the bite of the front teeth, and such other parts as may be desired.

What we claim is:

1. A dental articulator having a pair of model 45 holders spaced apart, a member projecting from the rear end of a first said holder toward the second thereof and rearwardly bent to form an extension, a portion of the surface of said extension adjacent said member, and facing this second of said holders, sloping rearwardly towards said 50 second holder, a pin positioned rearwardly of said sloping surface, secured to and projecting from said extension towards and beyond said second holder, a block, longitudinally slotted to receive said pin, disposed thereover and against 55 said extension, a nut on said pin adapted to retain said block, said block having a flanged portion complementary to and adapted to engage the end of said extension, a spring secured to 60 said first holder, engaging and urging said flange against said end, means hinging the rear end of said second holder to the laterally opposite sides of said block, and an adjustable screw threadedly 65 engaging said second holder and adapted to rest on said sloping surface. 65

2. A dental articulator having a pair of model 70 holders spaced apart, a member projecting from the rear end of a first said holder toward the second thereof and terminating in a rearward extension having a squarely faced end, a pin secured to and projecting from said extension toward, and beyond, said second holder, a block, longitudinally slotted to receive said pin, disposed 75 thereover and against said extension, a nut on said pin adapted to retain said block, said block 75

having a flanged portion complementary to, and adapted to engage, the end of said extension, a spring secured to said first holder, engaging and urging said flange against said end, and means hinging the rear end of said second holder to the laterally opposite sides of said block.

5. A dental articulator having a pair of model holders spaced apart, a member projecting from the rear end of a first said holder toward the second thereof and terminating in a rearward extension, a pin secured to said extension and projecting therefrom toward, and beyond, said second holder, a block, longitudinally slotted to receive said pin, disposed thereover and against said extension, means on said pin adapted to slidably retain said block, said block having a flanged portion complementary to the end of said extension, and adapted to cooperate with said end to longitudinally center said block, a spring secured 10 to said first holder, engaging and urging said flange against said end, and means hinging the rear of said second holder to the laterally opposite sides of said block.

6. A dental articulator having upper and lower model holders spaced apart, a member projecting upward from the rear end of said lower holder, said member being bent into a substantially horizontal extension and having a substantially flat rear end, a pin secured to and projecting upward from said extension beyond said upper holder, a block having a substantially flat rear end and longitudinally slotted to receive said pin, disposed

over said pin and against said extension, means on said pin adapted to slidably and oscillatably retain said block, a flat spring secured to said lower holder, engaging against, and urging said block forward, means hinging the rear end of said upper holder to the laterally opposite sides of said block; and means carried by said block and co-operating with the flat end of said extension, for retracting said block and first holder relatively to said second holder on relative lateral movement 10 of said holders.

7. A dental articulator having a pair of model holders spaced apart, the first of said holders having a substantially flat rear end, a member centrally disposed at the rear end of the second of said holders, said member having a substantially flat rear end, means pivoting said second holder to the opposite sides of said member, means, centrally disposed adjacent the rear end of said first holder, slidably and oscillatably mounting said member on said first holder, resilient means carried by said first holder engaging against the rear end of said member and urging said member forward relatively to said first holder, and said second holder into longitudinal 25 alinement with said first holder, and means carried by said member and cooperating with the flat rear end of said first holder, for retracting said second holder relative to said first holder on relative lateral movement of said holders. 30
